UNITED STATES PATENT OFFICE.

GEORGE WILLIAM WILLARD, OF SHERBROOKE, QUEBEC, CANADA, ASSIGNOR OF ONE-THIRD TO CYRUS A. FRENCH, OF SHERBROOKE, QUEBEC, CANADA, AND ONE-THIRD TO LOCKHART RAND WILLARD, OF EAST ANGUS, QUEBEC, CANADA.

PIPE-WRENCH.

1,225,909.

Specification of Letters Patent.

Patented May 15, 1917.

Application filed March 16, 1916. Serial No. 84,706.

To all whom it may concern:

Be it known that I, GEORGE WILLIAM WILLARD, a subject of the King of Great Britain, and resident of 4^a Kingston avenue, 5 Sherbrooke, Quebec, Canada, have invented certain new and useful Improvements in Pipe-Wrenches, of which the following is the specification.

The invention relates to improvements in 10 pipe wrenches as described in the present specification and illustrated in the accompanying drawings that form part of the same.

The invention consists essentially of the 15 novel construction and arrangement of parts set forth in detail hereinafter.

The objects of the invention are to devise 20 a wrench that will grip tighter and loosen easier than wrenches for pipe work usually do, to save time for the working and thereby economize in the employment of labor and generally to provide a cheap, durable and efficient tool.

In the drawings, Figure 1 is a plan view 25 of the wrench complete.

Fig. 2 is a plan view showing two parallel bars removed.

Like numerals of reference indicate corresponding parts in each figure.

Referring to the drawings, the numerals 30 1 and 2 indicate the jaw members and these are formed with the gripping teeth 3 and 4 on the inner faces, said faces describing dif-

ferent curves and at their inner ends nearly meeting. At the said inner ends of the jaw 35 members, the beveled inner faces 5 and 6 begin and these extend to the shanks proper 7 and 8.

The shanks 7 and 8 are thus spread 40 though parallelly arranged and toward the end have the arc-shaped recesses 9 and 10, into which the handle 11 fits by means of the curved lugs 12 at the end.

The pins in pairs 13 and 14 project outwardly from the shanks 7 and 8, each pair 45 being joined by a parallel bar, the pins 13 by the bar 15 and the pins 14 by the bar 16.

These pins are pivotally connected by the 50 said bars 15 and 16, so the operation of the handle moves the jaws in and out and toward one another.

What I claim is:—

The combination of two jaw members having gripping faces and shanks therefrom and arc-shaped recesses in said shanks, 55 a handle having lugs at the end engaging in said recesses and two pairs of parallel bars joining said jaw members and pivotally workable thereon on the turning of said handle.

Signed at Montreal, Canada, this 12th day of February, 1916.

GEORGE WILLIAM WILLARD.
